(57) **CLAIM**

The ornamental design for a safety seat for a child, as shown and described.

DESCRIPTION

FIG. 1 is a front view of the safety seat for a child;
FIG. 2 is a rear view thereof;
FIG. 3 is a left side view thereof;
FIG. 4 is a top plan view thereof;
FIG. 5 is a bottom view thereof;
FIG. 6 is a right side view thereof;
FIG. 7 is a cross-sectional view taken along line 7—7 of FIG. 4;
FIG. 8 is a perspective view thereof;
FIG. 9 is a perspective view of the safety seat for a child in a closed state; and,
FIG. 10 is a figure showing a child seated in the safety seat. The broken line of the child in FIG. 10 is for illustrative purposes only and forms no part of the claimed design.
